UNITED STATES PATENT OFFICE.

CHARLES STEWART FORBES, OF STRATHDON, SCOTLAND.

HATCHING APPARATUS.

1,285,971.

Specification of Letters Patent. Patented Nov. 26, 1918.

Application filed March 8, 1916. Serial No. 82,986.

To all whom it may concern:

Be it known that I, Sir CHARLES STEWART FORBES, baronet, a subject of His Majesty the King of England, residing at 5 Strathdon, in the county of Aberdeen, Scotland, Kingdom of England, have invented certain new and useful Improvements in Hatching Apparatus, of which the following is a specification.

This invention relates to improvements in hatching appliances or incubators for hens' or other eggs and it refers more specifically to devices of the kind comprising a box or casing which is divided into three compartments by means of partitions, the two side compartments serving to contain the heating devices and the intermediate compartment for the reception of the eggs.

The present invention consists in the heating and ventilating arrangement according to which the air entering the two side compartments flows upward past the heating devices and the water inward over the upper edges of the partitions and down 25 through the eggs, escaping from the intermediate egg compartment below the level of the said eggs as hereinafter described.

The invention as designed for electric heating is hereinafter described with reference to the accompanying drawings, in which:—

Figure 1 is a front elevation of the improved appliance.

Fig. 2 is a plan view thereof without the 35 lid or cover.

Fig. 3 is a side elevation;

Figs. 4 and 5 are transverse sections taken respectively on the lines 4—4 and 5—5 of Fig. 2; and

Fig. 6 is a diagram of the electrical connections.

As shown the incubator consists of a rectangular box or casing *a* made of wood or other suitable material and which is divided into three compartments *a'*, *a''* and *a³*. The two narrow compartments *a'* and *a''* on each side contain the electric heaters *b* and the wide space *a³* in the middle the eggs. *c*.

The partitions *d* between the two side heating compartments *a* and *a''* and the center or egg compartment *a³* do not as shown reach to the top of the box *a* but leave a space for air to pass say an inch between the upper edge of the box and the top of the partitions which latter are made easily

movable. The box *a* is provided with a lid *e* hinged from the back at *e'* and in construction may follow the usual practice in incubators. A frame *f* of wood or other similar material is mounted upon battens *a* fixed to the front and back of the box within the egg compartment *a³* at a convenient distance from the bottom which frame *f* is covered with perforated metal sheet *h*. The frame *f* does not as will be seen from Fig. 5 extend the full width of the egg compartment but a space of say two inches on each side is left to accommodate a roller *i* preferably made of wood, on each side. These 70 rollers *i* are carried on spindles and are provided with handles or milled edged disks *j* fixed to an extension of each spindle which passes through the front of the box *a*.

Upon these rollers and attached thereto 75 at each end is a single band of canvas or other suitable pervious material *k* which when wound around both rollers rests on the perforated metal *h*, the eggs *c* being placed thereon. Thus by simply giving a 80 turn to one of the disks *j* all of the eggs can be reversed in the known manner at a single operation. For use during the first eighteen days of the hatching, another frame *l* carrying cross strips *m* of thin wood or 85 metal is supported above the space between the rollers *i* with the said cross strips *m* at right angles to the band of cloth *k* and parallel with the said rollers. The spaces between the strips *m* are of such width as to 90 allow the eggs to be placed between, leaving only a small clearance space.

The electrical heaters *b* are placed close to the bottom of the two side compartments *a'* and *a''* and are preferably formed of high 95 resistance wire wound on a suitable fire proof insulator.

Air holes *n* are bored either in the bottom or quite low down in the sides of the heating spaces *a'*, *a''* to allow the air to enter 100 the incubator, and other outlet holes *o* are bored back and front in the walls of the incubator below the level of the eggs but above the level of the aforesaid inlet holes *n* in the sides. The air thus, as shown by the arrows on the drawings, passes in below the heaters *b* at the sides, is heated, rises over the partition *d* and then descends through the eggs *c* and out at the outlet holes *o* back 105 and front.

In order to provide the correct amount of moisture to the eggs during hatching, I

place two long narrow metal trays *r* containing water over the top of the heaters *b* their upper edges being almost level with the top of the partitions *d* between the heating compartments *a'* *a''* and the egg compartment *a³*. Thus the warmed air takes up moisture from the water in the trays *r* and seeing that the temperature decreases as the air descends in the egg compartment *a³* the moisture becomes condensed on the eggs in proper proportion to the state of the atmosphere.

In order to control the temperature of the incubator with certainty and accuracy it is found advisable to increase or diminish the amount of current passing through the heaters but not to cut off the current entirely at any time. To this end a regulating capsule or thermostatic control device *s* of any well known type is suspended from the lid *e* of the incubator so as to be placed just above the eggs and near the center in the manner common to most incubators. A small steel rod *t* operated by the expansion of the regulating capsule *s* presses upward upon a regulating screw on a rocking arm *u* which is pivotally mounted at *p* and carries a platinum or platinized contact piece *u'* which contact piece normally rests upon a second contact piece *v* and so arranged that when the above mentioned contacts are touching the full current passes from one of the terminals which may conveniently be arranged on the lid *e* through the heaters *b* and along the arm *u* to the other terminal, and the temperature in the incubator tends to rise. In parallel with this regulating device and also preferably on the outside of the lid I insert an electrical resistance *w* as indicated in Fig. 6. 40 in such a manner that when the capsule *s* expands and separates the two contact pieces *u'* and *v* on the regulator the electrical current instead of passing along the arm *u* is obliged to pass through the resistance *w* and the heating power of the heaters *b* is thereby reduced, the temperature in the incubator then tending to fall. In this manner the temperature can be accurately regulated without any sudden changes of temperature. 45 It will be obvious that the connections between the thermostatic control device on the hinged lid and the electric heaters *b* must be made by means of flexible connections as also must be those between the supply mains and the terminals if the latter are placed on the lid.

Conveniently a small pilot lamp *x* may as shown be mounted inside the incubator and be connected by a switch across the terminals 60 of the heaters *b*. This lamp *x* is therefore affected by the action of the regulator and indicates the action of the same, and can be

turned off when not required. It also serves the purpose of showing a light inside the incubator by means of which the eggs can be 65 inspected through glass windows *y* in the front of the incubator without opening the lid *e*.

It will thus be understood that with an appliance constructed according to the present invention the temperature can be regulated to a nicely; further the eggs are never shaken when the lid is opened for inspection purposes. The damping arrangement for the eggs gives a correct amount of moisture, rendering the sprinkling of eggs with water unnecessary. When the incubator is opened for airing and turning the eggs, all foul air escapes, the egg turning arrangement is simple and certain in its action and also the incubator can be very easily cleaned out after use.

It will be obvious that the improved appliance could be arranged by making slight modifications for oil lamp, or hot water, heating, in which case the capsule and regulating lever could be employed as at present but in the known manner for the purpose of raising a damper or dampers situated on the top of the heating chambers, forming a by-pass 80 and allowing the surplus heat to escape.

What I claim is:—

A hatching appliance comprising a box having an airtight imperforate base and an airtight cover, a pair of vertical partitions rising from the bottom of the box, with their upper ends spaced from the cover, said partitions extending from one side of the box to the opposite side, and being spaced inwardly from the other two sides, thereby dividing the box into two side compartments and an intermediate compartment, electric heating devices arranged within each of the two side compartments above the base, water troughs in the side compartments above the heating devices, a perforated sheet, a single band of pervious material resting on the said sheet, said sheet with said band thereon being located within the intermediate compartment for supporting the eggs above the bottom of said compartment, and means for moving said band for the purpose of reversing the eggs when required, the side compartments having air inlets arranged in the sides of the box from one end thereof to the other and below the level of the heating devices, but above the base, the intermediate compartment having air outlets through the other two sides of the box below the level of the supporting sheet and pervious band and also above the base.

In testimony whereof I have signed my name to this specification.

CHARLES STEWART FORBES.
